DESIGN FOR A COMBINED CASE AND CONNECTOR FOR A HEARING AID RECEIVER**Alfred L. W. Williams, Cleveland Heights, Ohio,
assignor to The Brush Development Company,
Cleveland, Ohio, a corporation of Ohio****Application March 20, 1939, Serial No. 83,696****Term of patent 14 years***To all whom it may concern:*

Be it known that I, Alfred L. W. Williams, a subject of the King of England, residing at 12415 Fair Hill Road, Cleveland Heights, in the county of Cuyahoga and State of Ohio, have invented a new, original, and ornamental Design for a Combined Case and Connector for a Hearing Aid Receiver, of which the following is a specification, reference being had to the accompanying drawing, forming part thereof.

Fig. 1 is a front elevational view of a case and connector for hearing aid receiver.

Fig. 2 is a top end elevation.

Fig. 3 is a side elevation; and

Fig. 4 is a bottom end elevation.

I claim:

The ornamental design for a combined case and connector for a hearing aid receiver, substantially as shown.

ALFRED L. W. WILLIAMS.
